UNITED STATES PATENT OFFICE

171,430

DOLL OR THE LIKE

Dorothy M. Tint, Brooklyn, N. Y.

Application April 27, 1953, Serial No. 24,677

Term of patent 7 years

(CL. D34—4)

To all whom it may concern:

Be it known that I, Dorothy M. Tint, have invented a new, original, and ornamental Design for a Doll or the like, of which the following is a specification, reference being had to the accompanying drawing, forming a part hereof.

Fig. 1 is a front elevational view of a doll or the like, showing my new design.

Fig. 2 is a side view in elevation; and
Fig. 3 is a back view in elevation.

I claim:

The ornamental design for a doll or the like, substantially as shown.

DOROTHY M. TINT.
